SHINGLE

Dozier Finley, Berkeley, Calif., assignor to The Paraffine Companies, Inc., San Francisco, Calif., a corporation of Delaware

Original application August 25, 1930, Serial No. 477,626. Divided and this application April 25, 1934, Serial No. 722,233

3 Claims. (CL. 108—7)

This is a division of my copending application Serial No. 477,626, filed August 25, 1930.

My invention relates to a shingle, and more particularly to an interlocking shingle.

5 It is among the objects of my invention to provide a shingle which is adapted to be more securely and permanently fastened to a roof.

Another object of my invention is to provide an interlocking shingle which may be secured in its 10 interlocked position with the use of a single nail.

10 A further object of my invention is to provide a shingle which may be laid to provide a roof presenting an improved thatch appearance.

The invention possesses other objects and features of advantage, some of which, with the foregoing, will be set forth in the following description of my invention. It is to be understood that I do not limit myself to this disclosure of species 15 of my invention, as I may adopt variant embodiments thereof within the scope of the claims.

20 Referring to the drawing:

Figure 1 is a perspective view of a roof portion showing the shingles laid in interlocked position.

25 Figure 2 is a plan view of the shingle embodying my invention.

In terms of broad inclusion, the shingle embodying my invention comprises a substantially square-shaped sheet, preferably of flexible composition roofing material. The shingle is provided 30 with locking means at one corner and complementary locking means at an adjacent corner adapted to engage with the locking means of an adjacently laid shingle. The shingles are laid in courses with each shingle interlocked with those 35 in the same course and also with those in adjacent courses. With shingles having a locking tab at one corner and a receiving slit at an adjacent corner, the interlocking is effected by a shingle laid in one course, a second shingle laid in an 40 underlying course and positioned with one of its corners overlapping the slotted corner of the first shingle, a nail through the lapping corners, and a third shingle laid in the course with the first shingle and positioned with its tabbed corner 45 overlying the nailed corners and with its tab engaging the slit of the first shingle.

In greater detail, the shingle embodying my invention comprises a substantially square-shaped sheet, preferably having straight sides. Locking means or a tab 2 is provided at one corner, and complementary locking means or a receiving slit 3 is provided at an adjacent corner. This 50 general outline of the shingle is clearly shown in Figure 2.

55 The shingles are preferably cut from a parent

strip of flexible composition roofing material. Such materials fall in the class generally known as prepared roofing materials, and comprise a suitable felt base saturated and/or coated with a bituminous compound, which may or may not be covered with crushed mineral matter. The particular shape of the shingles permits them to be cut from a parent strip without waste of material. When the shingles are formed the locking tab 2 is provided by cutting a recess 4 in the 10 corner near the receiving slit 3 of an adjacent shingle.

In the preferred method of laying the shingles, and beginning at the left end of the roof eaves as shown in Figure 1, a shingle with its tab removed is nailed down by a nail passing through the slotted corner. This nail would pierce the shingle at the point indicated at 6 in Figure 2. This first shingle is also fastened with a nail 7 at its lower left-hand corner. The locking tab 2 20 of another shingle is now engaged with the receiving slit 3 of the fixed shingle, so that the lower edge of the shingle is in line with the lower edge of the one first laid; and the second shingle is fastened with a nail at its slotted corner. 25 Other shingles are now laid in a similar manner until a course has been completed along the eaves of the roof.

A second course of shingles is now laid to overlap the first course. These shingles are laid 30 with their side edges vertically aligned with those in the underlying course. As each shingle in this course is laid its slotted corner is slipped under the upper left-hand corner of a shingle in the underlying course. In other words, a plain or 35 non-locking corner of a shingle in the underlying course overlies a slotted corner of a shingle in the overlying course. It is to be noted that the overlapping corner abuts the side of the receiving slit 3, thus providing means for aligning the shingles 40 in position. A nail is then driven through the overlapping corners so that both shingles are caught, as illustrated by the nail 8 of a later applied shingle.

When the shingles in the second course are laid 45 they are positioned with the tabbed corners overlying the nailed corners and with the tabs engaging the slit of an adjacently laid shingle. As a result, a non-locking corner of each shingle in an underlying course is interposed, and nailed between the locked corners of adjacent shingles in an overlying course.

Throughout the body of the roof a uniform laying will be found, viz., a shingle will be found in one course, a second shingle will be found in 50 55

an underlying course and positioned with one of its corners overlapping the slotted corner of the first mentioned shingle, a nail will be found through these lapping corners, and a third shingle will be found in the course with the first shingle and positioned with its tabbed corner overlapping the nailed corners and arranged with its tab engaging the slit of the first shingle. This arrangement of shingles gives a secure and permanent fastening, and with but a single nail employed for each shingle.

In the first vertical row of shingles extra nails are employed to hold down the lower left-hand corners, but in the body of the roof the same number of nails are employed as there are shingles. As shown in Figure 1, the shingles are aligned in rows running transversely and longitudinally of the roof. This gives a uniform square thatch which is pleasing in appearance.

20 I claim:

1. In a roof comprising a plurality of shingles having a pair of locking corners and a pair of non-locking corners, a shingle laid in one course, a second shingle laid in an underlying course and positioned with one of its non-locking corners overlapping a locking corner of said first shingle, a nail through said lapping corners, and a third shingle laid in a course with the first shingle and positioned with a locking corner overlapping said 25 nailed corners and interlocked with the locking corner of the first shingle.

2. In a roof comprising a plurality of shingles

having a pair of locking corners and a pair of non-locking corners, a shingle laid in one course, a second shingle laid in an underlying course and positioned with one of its non-locking corners overlapping a locking corner of said first shingle, another shingle in the underlying course and positioned with one of its non-locking corners underlapping said lapped corners, a nail through all three of said lapping corners, and a fourth shingle laid in a course with the first shingle and positioned with a locking corner overlapping said 10 nailed corners and interlocked with the locking corner of the first shingle.

3. In a roof comprising a plurality of rectangular shingles having a locking tab at one lower corner, a receiving slit at the other lower corner, and having plain right angular upper corners, a shingle laid in one course, a second shingle laid in an underlying course and positioned with one of its plain corners overlapping the slotted corner of said first shingle and with its upper edge adjacent the upper end of the slit, another shingle in the underlying course and positioned with one of its plain corners underlapping said lapped corners and also having its upper edge 25 adjacent said slit, a nail through all three of said lapping corners, and a fourth shingle laid in a course with the first shingle and positioned with its tabbed corner overlapping said nailed corners and with its tab engaging said slit of the first 30 shingle.

DOZIER FINLEY.
